UNITED STATES PATENT OFFICE.

EUGÈNE BARDOLLE, OF PARIS, FRANCE.

CENTRIFUGAL SEPARATOR.

SPECIFICATION forming part of Letters Patent No. 717,963, dated January 6, 1903.

Application filed September 3, 1901. Serial No. 74,246. (No model.)

To all whom it may concern:

Be it known that I, EUGÈNE BARDOLLE, engineer, a citizen of the French Republic, residing at 28 Rue St. Lazare, Paris, France, have invented certain new and useful Improvements in Centrifugal Separators, of which the following is a specification.

This invention has for its object an apparatus for the separation of mixed gaseous bodies of different specific gravities, in which apparatus the action of centrifugal forces on the particles of the mixture being operated on are made use of to effect the object in view.

It is well known that the force which tends to separate two neighboring molecules of different masses is proportional to the difference of the masses of these particles and to the square of the tangential component of their velocity of rotation.

Many attempts have been made in order to apply the principle of apparatus constructed for the separation of solids and liquids to the separation of gases. I have found that the success of the results depends on the shape of the vessel in which the gases are treated and that the best shape to be given to the revolving surfaces in the rotating vessels is that of a paraboloid, because paraboloids are what may be termed "level surfaces of a rotating fluid."

In order that my invention may be clearly understood, I will describe the same with reference to an apparatus constructed for separating from a certain mixture of gases the carbon dioxide and the hydrogen which it contains, the composition of such a mixture being as follows: CO_2 , 21.33 per cent.; CO , 22; CH_4 , 12.47; H , 44.20.

Said apparatus is illustrated in the accompanying drawings, in which—

Figure 1 is a vertical section of the apparatus; Fig. 2, half of a horizontal cross-section on the line A B of Fig. 1, and Fig. 3 a section and a plan of one of the apertures provided in the walls of the revolving drum and in the bottom plate which separates each casing from the chamber arranged above it.

a and *b* are revolving drums, while *c* is a stationary casing. The revolving drums are connected in any suitable manner to a vertical spindle *d*—for instance, by means of iron pieces *e*—and the stationary casing is mount-

ed on a fixed support *f*. The vertical spindle *d*, the ends of which are guided by stepped bearings *g* of suitable pattern, is given a rotary motion by means of any suitable gearing, such as wheels, pulleys, endless screws, and the like. In the arrangement shown in Fig. 1 the shaft *h* is connected to the intermediate shaft *j* by means of the separate wheel *i* and actuates the spindle *d* by means of a helical gear comprising a worm-wheel *k*, keyed on the shaft *j*, and a work *m*, cut on the spindle *d*. Above the casing and drums are arranged three closed casings *n o p*, forming three concentric chambers *n' o' p'*, communicating, respectively, as hereinafter described, with the chambers formed by the casing *c* and drums *a b*. A central tube *r* surrounds the axle *d*, which is free to revolve therein. Each chamber *n' o' p'* communicates with the branch pipe *s*, fitted with a flange *t*, to which a regulating-cock, permitting of adjusting the issue of the gas, is fixed. The inlet of the mixture of gas to be separated occurs through the branch pipe *u*, integral with the aforesaid support *f*. The gases on being separated pass through apertures *v*, Figs. 2 and 3, provided in the walls of the revolving drums *a* and *b*. In order to insure that these apertures do not offer any resistance to the flow of the gas through them, (a disadvantage which would occur if the apertures were situated in a plane tangent to the drums,) the sheets of metal forming the walls of the drums are bent outward, as shown in Fig. 3, during the operation of making these apertures, so that the latter are in meridian planes of a solid generated by the revolution of a paraboloid, or, in other words, these apertures are normal to the trajectory of the gaseous molecules set in motion during the rotary movement of the drums. The apertures provided in the bottom plate *w* of the chambers *n' o' p'* have the same shape. Annular openings *y* and *z* may besides help provide for the passage of the heavier and lighter gases, respectively, the said annular openings being arranged on the outer periphery and around the center of the bottom plate. The drums *a* and *b*, which, as stated, are in the form of paraboloids, are preferably constructed of thin sheet-steel, cut out in the direction of the height through meridian cross-sections of the paraboloids,

special machinery being used in forming the apertures for the passage of the gaseous molecules. The plates are then welded together.

The hereinbefore-described apparatus is more specifically designed with a view to its being utilized for the following purposes: first, elimination of the solid or liquid molecules carried by the gases; second, extraction of the carbon dioxid from ordinary generator-gas, such as Mond gas, Dowson gas, and Riche gas—which gases have about the composition above given and which gases contain twenty per one hundred thereof by volume and fifty per one hundred by weight of dioxid, a proportion which may be further increased by decomposing carbonates in the retorts; third, extraction of the hydrogen from such a gas, which contains forty per one hundred thereof by volume; fourth, extraction of oxygen from the air in a state of purity sufficient to allow of this gas being used in the oxyhydrogen blowpipe simultaneously with the hydrogen extracted by the same means, these various applications being susceptible of being effected in their entirety, or partly, in a single installation.

One and the same gas-works may have the advantage of producing economically the motive power it requires by utilizing in internal-combustion engines the carbon monoxid and the hydrocarbons which form forty per cent., by volume, of the gas, these latter being more than sufficient to drive the separators and compressors, by means of which the gases that are collected separately are stored under high pressure in special reservoirs and the like.

Having thus fully described my invention, what I claim as new, and desire to secure by Letters Patent, is—

1. In an apparatus for separating fluids by means of centrifugal force, a casing in the

form of a paraboloid, revolving drums of the same form and having the same axis, and provided with apertures *v*, closing-plates for the casing and drums of the same forming separate concentric chambers, an inlet-pipe to admit the mixture of gases, outlet-pipes for the fluids separated, and means for rotating the drums, substantially as described. 45 50

2. In an apparatus for separating fluids by means of centrifugal force, a casing in the form of a paraboloid, revolving drums of the same form and having the same axis and having apertures *v*, closing-plates for the casing and drums forming separate concentric chambers, a pipe for the admission of the mixture of gases, the walls of the revolving drums being bent outward to form the said apertures *v* in meridian planes of a solid generated by 55 the revolution of a paraboloid, outlet-pipes for the separated fluids, and means for rotating the said drums, substantially as described.

3. In an apparatus for separating fluid by 65 means of centrifugal force, a casing in the form of a paraboloid, revolving drums of the same form and having the same axis, and being provided with apertures *v*, closing-plates for the casing and drums forming separate 70 concentric chambers, a pipe for the admission of the mixture of gases, outlet-pipes for the separated fluids, a spindle supporting the revolving drums, a worm-screw on the end of this spindle, a toothed wheel gearing with 75 this worm-screw, and means for rotating said toothed wheel, substantially as described.

In testimony whereof I have hereunto set my hand in presence of two subscribing witnesses.

EUGÈNE BARDOLLE.
